FOLDING DEVICE

Harold Howe, New York, N. Y., assignor to Howe
Folding Furniture, Inc., New York, N. Y.

Application July 17, 1931. Serial No. 551,408

7 Claims. (Cl. 211—93)

My invention relates to a folding device particularly adaptable for shelves, tables, and the like and the principal object of which is to provide means for folding a pair of surface sections

5 with extreme compactness and in a manner to require a minimum amount of space for the folding operation and for the storage of the sections when folded.

One important object of my invention is to 10 provide a folding means for a pair of sections which permits folding the same downwardly within a space substantially the length of the sections. This affords a very convenient shelf device particularly when a shelf is desired on a 15 wall surface at a point where folding space either up or down with respect to the shelf is at a premium or extremely limited.

A further object of my invention lies in the 20 provision of a foldable article such as a shelf which when unfolded provides a very rigid and substantial support of double section size and which when folded occupies a space of substantially the same length as only one of said sections.

25 Still another object of my invention lies in the provision of a novel folding link and supporting means for the sections when in unfolded or coplanar position.

My invention is particularly adaptable for use 30 on shelves such as may be provided on walls in kitchens and elsewhere where space saving is important and I have illustrated and will describe my invention in detail as applied to the shelf. It should be clearly understood that the 35 same folding means is adaptable for other articles and uses as well, such as built shelves, tables, etc.

Other objects and advantages of my invention 40 will be apparent as the description now proceeds, reference being had to the figures of the accompanying drawing forming a part of this application and wherein like reference numerals indicate like parts.

In the drawing:

45 Figure 1 is a side view of a shelf embodying my invention in unfolded or operative position, the dotted lines showing the manner of folding the shelf.

Figure 2 is a side view of the shelf in completely 50 folded position.

Figure 3 is a bottom plan view of the unfolded shelf shown in Figure 1.

Figure 4 is a perspective view of the shelf in unfolded position.

55 The reference number 1 indicates a supporting

surface such as a wall, secured to which are the horizontal and vertical supporting members 2 and 3 respectively suitably rigidly mounted on the wall.

Suitably rigidly secured to the horizontal supporting member 2 is a spacing member 4 to the lower front edge of which is hinged as at 5 the section 6 of the shelf whereby said section may pivot or hinge downwardly to a position substantially parallel with the wall as shown clearly in 60 Figure 2. Secured to each side edge of the section 6 adjacent the outer end thereof are metal brackets 7 to which are pivoted as at 8 similar brackets 9 secured to the side edges of the outer section 10 of the shelf adjacent the rear end thereof 70 whereby said section 10 is pivoted to the section 6 in a manner to fold upwardly with respect thereto as indicated clearly in dotted lines in Figure 1 and in full lines in Figure 2. The metal brackets 7 and 9 are provided with cooperating 75 ears 11 through which the pivot pins 8 extend. The arrangement of this pivot connection between sections 6 and 10 is such that when the sections are unfolded to the position shown at Figures 1, 3, and 4, the upper surfaces of the 80 sections will be flush with each other and the adjoining ends abutting, thus providing a smooth double section shelf surface.

Mounted upon the vertical supporting member 3 is a bracket 12 provided with an angular extending ear 13 to which is pivoted as at 14 one end of a link 15 bent slightly upwardly as at 16 adjacent its outer end. The outer end of this link 15 is pivoted as at 17 to one end of a locking and supporting strip 18 suitably rigidly secured 90 at its opposite end to the underside of the section 10 as at 19. The end of the strip 18 to which the link 15 is pivoted extends beyond the end of the section 10 to substantially underlie the adjacent end of the section 6 as shown clearly in 95 Figure 3.

Secured as by screws 20 to the underside of the section 6 are brace strips 21, the outer ends of which project beyond the end of the section 6 to underlie the adjacent end of the section 10 when 100 the sections are in unfolded position.

There is thus provided a very rigid brace for the shelf sections when in unfolded position, capable of supporting a very considerable weight on either or both of the sections 6 and 10 without 105 danger of disturbing the shelf.

When it is desired to fold the shelf back out of the way it is merely necessary to lift up on the outer end of the outer section 10 whereupon the sections hinge at the points 8 and inward pres- 110

sure towards the wall 1 on the section 10 causes the sections to fold downwardly together as clearly illustrated in Figures 1 and 2.

I have thus provided a very effective shelf occupying but very small space and requiring little space for folding and unfolding and which is of very few parts and easily operated.

Of course, changes may be made in details of construction and arrangement of parts without departing from the spirit and scope of my invention. I do not limit myself, therefore, to the exact form herein shown and described other than by the appended claims.

I claim:

15. 1. A folding device comprising in combination a pair of sections pivoted together and foldable to and from co-planar relation, members on each of said sections having portions overlapping the other section when in co-planar relation, said members being disposed substantially centrally of the width of said sections, a support for said sections, and a single link pivoted to said support and to one of said members.

25. 2. A folding device comprising in combination a pair of sections pivoted together and foldable to and from co-planar relation, a supporting member rigid with the underside of one of said sections and overlapping the other section when in co-planar relation, said members being disposed substantially centrally of the width of said sections, a support for said sections, and a single link pivoted to said support and to said member.

35. 3. A folding device comprising in combination a pair of sections pivoted together and foldable downwardly from co-planar relation, a support to which one of said sections is pivoted and means for supporting said sections in unfolded position comprising a single link pivoted to said support at one end and to an overlapping member carried by one of said sections at its opposite end and substantially centrally thereof.

45. 4. A folding device comprising in combination a support, a surface section hinged thereto, a second surface section pivoted to said first section for folding downwardly therewith to a position substantially parallel with said support, a member secured to one of said sections and overlapping the other, said member being disposed substan-

tially centrally of the width of said sections, and a single link pivoted to said support and to said member whereby to support said sections in unfolded co-planar position.

5. A folding device comprising in combination 80 a support, a surface section hinged thereto, a second surface section pivoted to said first section for folding downwardly therewith to a position substantially parallel with said support, a member secured to one of said sections and overlapping the other, a single link pivoted to said support and to said member whereby to support said sections in unfolded co-planar position, and additional supporting members secured to one of said sections and underlying the other section when in co-planar relation, said members being disposed substantially centrally of the width of said sections.

6. A folding device comprising in combination 85 a support, a surface section hinged thereto, a second surface section pivoted to said first section for folding downwardly therewith to a position substantially parallel with said first section and said support, a bracing member secured to the underside of said second section and substantially centrally thereof and having a portion underlying said first section when said sections are unfolded to co-planar relation, and a single link pivoted to said support and to the underlying portion of said bracing member.

7. A folding device comprising in combination 100 a support, a surface section hinged thereto, a second surface section pivoted to said first section for folding downwardly therewith to a position substantially parallel with said first section and said support, a bracing member secured to the underside of said second section and having a portion underlying said first section when said sections are unfolded to co-planar relation, a single link pivoted to said support and to the underlying portion of said bracing member, and additional bracing members secured to said first section and having portions underlying said second section when in co-planar relation, said members being disposed substantially centrally 115 of said sections.
